UNITED STATES PATENT OFFICE.

PIERRE MARIE JOSEPH LAFLÈCHE, OF PARIS, FRANCE, ASSIGNOR TO SOCIÉTÉ
LAFLÈCHE FRÈRES, OF PARIS, FRANCE.

BRACES.

Application filed November 10, 1920. Serial No. 423,154.

To all whom it may concern:

Be it known that I, PIERRE MARIE JOSEPH LAFLÈCHE, a citizen of the French Republic, residing at No. 69 Rue Reaumur, Paris, France, have invented certain new and useful Improvements in and Relating to Braces, of which the following is a specification.

Braces for holding trousers as have hitherto been proposed, comprise generally, whatever their system may be, a vertical piece which is applied on the back and two straps branching from the said piece and passing over the shoulders.

15 The assemblage of the said pieces necessitates cutting and sewing operations, and requires a strengthening which is often made by means of leather or pieces of cloth.

All those arrangements are expensive and 20 they determine a right side and a wrong side of the braces.

On the other side, the length is adjusted by means of buckles and pressure clips, which are incommodious, stain the shirts 25 and are very expensive.

The present invention relates to improved braces which are made of one piece and may be made without any metallic part, thus avoiding the above drawbacks.

30 In principle, the new braces are made of one strap of fabric, cloth or elastic band which is bent in the shape of a V, the back tabs being passed through the bottom of the V and the two ends of the strap being provided with the front tabs secured thereto by any suitable means.

Preferably, the said single strap is made 35 of two superposed fabrics, held together at certain intervals by sewing or preferably 40 by means of warp threads inserted in the two fabrics, thus forming compartments in which it is possible to pass the above tabs, whereby the length of the braces may be adjusted at will.

45 The invention is illustrated, by way of example only in the accompanying drawing, in which:

Fig. 1 is a front view of the new braces.

Fig. 2 shows a developed strap forming 50 the braces.

Figures 3, 4 and 5 show details.

Fig. 6 is a diagram illustrating the man-

ner of weaving the material from which the braces are made.

As shown in the drawing, the new braces 55 are made of a strap *a* made of fabric, cloth or elastic band, bent as shown in Fig. 1.

The back tab *b* is inserted in the bend of the strap and the front tabs *c* are secured to its free ends.

60 The strap *a* is preferably made of two superposed fabrics *d e* Fig. 4, interconnected at intervals, along lines *f* by sewing or by means of warp threads passing in the two fabrics. Compartments or pockets *g* are 65 thus formed through which the tabs *b* and *c* may be passed.

In the diagram shown in Fig. 6, *h* designates the upper textile warp threads; *i* designates the lower textile warp threads; *j* 70 the upper elastic warp threads; *k* the lower elastic warp threads; *l* the upper weft threads and *m* the lower weft threads. The part designated by A comprises seventy-six upper and seventy-six lower weft threads, 75 only a few of which are shown. Part B, that is, the part corresponding to *f* in Fig. 5 has four upper and four lower weft threads. Part C has eight upper and eight lower weft threads. Part D has four upper 80 and four lower weft threads and part E has seventy-six upper and seventy-six lower weft threads, only a few of which are shown.

The above division into compartments or pockets may be made along the entire length 85 of the strap or only along those parts in which the tabs are placed.

The two fabrics constituting the strap may be of different widths.

It will be readily seen that the new braces 90 are reduced to a minimum of elements, that their manufacture is considerably simplified and the cost price considerably reduced. All the drawbacks due to the metallic parts and to the presence of leather are thus avoided.

95 I wish it to be understood that the above arrangements are given by way of example only. The shapes, sizes, materials which are used, and all modifications of detail may be varied without in any way departing from 100 the spirit of the invention.

What I claim is:—

A suspender formed of a single strap folded intermediate its ends into V-shaped

formation, said strap consisting of superposed strips of woven material connected together throughout the length of the strap at equally spaced points by woven threads of the material, the spaces between the connected portions of the strips providing equally spaced pockets, tabs extending through pockets arranged near the ends of

the strap, and another tab extending through a pocket at the folded portion of 10 the strap.

The foregoing specification of my "Improvements in and relating to braces," signed by me this 20th day of October, 1920.

PIERRE MARIE JOSEPH LAFLÈCHE.
